POCKET COMB

Paul E. Brooks, 14351 Woodmont,
Detroit, Mich. 48227

Filed Nov. 24, 1969, Ser. No. 20,262

Term of patent 14 years

Int. Cl. D28—03

U.S. Cl. D86—8

FIG. 1 is an exploded perspective view of a pocket comb showing my new design, side opposite that shown being identical thereto.

FIG. 2 is a plan view thereof partly assembled.

FIG. 3 is a plan view thereof more fully assembled.

FIG. 4 is a plan view thereof fully assembled.

FIG. 5 is a side elevational view thereof.

I claim:

The ornamental design for a pocket comb, substantially as shown and described.
